LIQUID CONTROL GEAR

Filed May 15, 1945

UNITED STATES PATENT OFFICE

2,416,366

LIQUID CONTROL GEAR

Fred R. Wittnebert, Chicago, Ill., assignor to
Sperry Products, Inc., Hoboken, N. J., a corpora-
tion of New York

Application May 15, 1945, Serial No. 593,894

4 Claims. (Cl. 60—54.5)

1

This invention relates to liquid control gear of the type wherein movement of a member at a transmitting station is caused to control movement of a member at a receiving station. More particularly, this invention relates to one-pipe systems wherein the movable members are normally under pressure. Such systems are disclosed, for example, in the patent to H. S. Hele-Shaw and T. E. Beacham No. 1,983,884, granted December 11, 1934, and in the patent to Alfred N. Lawrence, No. 2,197,554, granted April 16, 1940. In the first of these patents, a constant force is applied to the liquid in every position of the transmitter handle to balance a constant force at the receiver. In the second patent, a continuously increasing force is applied to the liquid in progressive positions of the transmitter handle to balance a similarly increasing load on the receiver. In either of the aforementioned cases, the operating and operated members are in normally balanced condition and will tend to retain any positions into which they may be moved.

However, unbalance may occur either because of variations in the load or because of expansion or contraction of the liquid in the transmission system. Such unbalance will tend to change the position of the receiver, or operated, member and thus introduce an error. It is therefore one of the principal objects of this invention to provide locking means adjacent the receiver which will normally lock the receiver in operated position so as to prevent actuation thereof by variations of load on the receiver or by expansion and contraction of the liquid.

It is a further object of this invention to provide locking means as described above which will unlock the receiver instantly and automatically in response to actuation of the transmitter handle in either direction to increase or decrease the pressure in the transmission line.

It is still another object of this invention to provide a liquid control gear in which any of a plurality of transmitters may actuate the same receiver without affecting the other transmitters. This is accomplished by interposing a brake of the type described above in the connection between each transmitter and the common receiver.

Further objects and advantages of this invention will become apparent in the following detailed description thereof.

The accompanying drawing is an assembly of a liquid control gear showing multiple transmitters and a common receiver, with brake elements applied thereto.

Referring to the drawing, there is shown a 55 operated oppositely to the transmitter. Similar

2

liquid control gear system comprising a plurality of transmitters or transmitter stations T and T' connected to a common receiver or receiver station R through single pipe connections CC' and CC''. These connections have in common the duct C, while the respective ducts C' and C'' from the transmitters T and T' are joined at the coupling J. Force applied to the liquid by transmitter handle H or H' is caused to move the liquid through the connection CC' or CC'' to actuate an operated member M.

For applying forces to the liquid column there may be provided in each transmitter T, T' a cylinder 10 within which operates a trunk type piston 11. Said cylinder is connected at one end to the connection CC' or CC'', which is filled with liquid extending up to said piston. For operating the said piston in a direction to transmit force to the liquid column, there may be provided a transmitting element in the form of a lever 15 connected to operating handle H and pivoted in casing 16 at 17, said lever having an arm 18 pivotally connected at 19 to the upper end of piston rod 20 pivotally connected to the piston at 21. As the handle is moved in the direction of the arrow, the piston is lowered to cause the column of liquid to move through the duct C'C. The force which is normally applied to the piston is determined by a loading spring 22 seated against a bracket 23 fixed upon a sleeve 24 pivoted at 25 within the casing 16. The other end of said loading spring bears against a bracket 26 fixed to a member 27 having a rod 28 slidable within the sleeve 24, so that said spring is extensible. The member 27 is pivoted at 29 to an arm 30 of lever 15. The position of the spring and its connections is such that the spring acts through a small lever arm to apply a slight loading force to arm 18 and the piston 11 when the piston is in its uppermost position, but as the handle H is actuated in the direction of the arrow it will be seen that the spring acts through an increasing lever arm. At the same time, however, the spring is extended so that while it acts through a larger lever arm it applies a decreasing force as said arm increases. The force applied to the piston 11, which is a product of the spring force and the lever arm, may be constant in every position of handle H, or it may continuously increase or decrease as the handle moves from one limiting position to the other, depending upon the design.

The force applied to the liquid column CC' is applied to the receiver which is fundamentally the same as the transmitter, but connected to be

parts bear the same numeral primed. When piston 11 is at the upper end of its stroke, piston 11' is at the lower end of its stroke, and downward movement of piston 11 causes upward movement of piston 11'. The force of spring 22' is the same as the force of spring 22, and lever arms 18' and 30' bear the same relation as lever arms 18 and 30. Therefore, all movements of handle H will be duplicated by member M.

A synchronizing mechanism is provided in the form of a valve 35 which normally closes communication by way of passage 37 between the fluid reservoir formed by the interior of casing 16 and the cylinder 10. At the upper end of the piston stroke, a pin 31 on handle H is adapted to rock a crank 32 around a pivot 33 to depress a rod 34 against the action of a spring 36 to open valve 32.

The transmitter T' is a duplicate of transmitter T and will similarly operate member M through connection C'C.

It is quite apparent that if the load on member M should change, or if the liquid in the connection CC' should expand or contract, the position of member M would be changed and an error in the operated member would thus be introduced. In order to hold the operated member M in operated position regardless of temperature changes of the liquid, or of changes in the load on the member, there is positioned in the connection between the transmitter and the receiver, but closely adjacent the receiver, a lock B.

The locking means B is provided with a cylindrical bore 50 within which slides a lapped piston valve 51. The bore 50 is closed at one end, and communicates at its other end at inlet 53 with the duct C' so that the liquid under pressure of piston 11 is applied axially to the piston valve 51 to tend to move the piston valve to the left. This tendency is balanced by a spring 52 which normally maintains the piston valve in balanced position, in which position the valve closes communication with duct C at inlet 54. Inlet 54 applies force from duct C radially with respect to the piston valve and therefore variations in pressure on member M will not affect the valve. It will now be seen that actuation of handle H in one direction or the other, will increase or decrease the pressure on the liquid in duct C' which will unbalance the piston valve 51 to move it in one direction or the other. Movement of the piston valve to the left will establish communication between the duct C' and the duct C directly through bore 50, while movement of the piston valve to the right, will establish communication between C and C' by way of passages 40 and 41 in the valve. As soon as handle H is no longer actuated, the balanced condition will again prevail on the ends of the piston valve which will be restored to balanced position to break the connection between ducts C' and C.

Thus, in the normal, balanced position of piston valve 51, the operated member M is locked in position and cannot be affected by changes in pressure in duct C, since the pressures in duct C are applied radially to the piston valve. Also, by making the total resistance to movement of the piston valve 51 greater than the resistance to movement of the piston 11, any changes in temperature in duct C' will vary only the position of the transmitter handle and will not affect the member M. The latter will therefore not be subject to errors in positioning due to temperature variations of the liquid in duct C.

Provision is made whereby member M of the

receiver may be actuated selectively from any of a plurality of transmitters, and provision is further made whereby any transmitter may be operated without affecting the other transmitters. Between the transmitter T' and the receiver there is provided a lock B', which is a duplicate of lock B, closely adjacent the receiver. The duct C communicates with inlets 54 and 54' by conduits branching from joint J. It will now be apparent that when transmitter T is operating, the variations in pressure produced in duct C will have no effect on transmitter T' because such pressure variations are being applied radially to the piston valve 51' in the closed position thereof. Similarly when transmitter T' is operating, the variations in pressure produced in duct C will have no effect on transmitter T because such pressure variations are being applied radially to the piston valve 51 in the closed position thereof. Thus, by the use of these locks, the receiver may be operated from either transmitter without affecting the other transmitter.

By placing locks B and B' closely adjacent the receiver, the ducts connecting the locks to the receiver are short and therefore there is relatively little liquid whose expansion and contraction can vary the setting of the receiver member M. The bulk of the liquid is contained between the locks and the transmitters so that temperature variations will affect the setting of the transmitter handles, as hereinbefore set forth, without appreciably affecting the position of the operated member M.

In accordance with the provisions of the patent statutes, I have herein described the principle and operation of my invention, together with the apparatus which I now consider to represent the best embodiment thereof, but I desire to have it understood that the apparatus shown is only illustrative and that the invention can be carried out by other equivalent means. Also, while it is designed to use the various features and elements in the combination and relations described, some of these may be altered and others omitted without interfering with the more general results outlined, and the invention extends to such use.

Having described my invention, what I claim and desire to secure by Letters Patent is:

1. A hydraulic remote control system comprising a plurality of transmitters, a receiver, means for connecting said transmitters to said receiver, said last-named means including a common duct and individual ducts leading from said common duct to the respective transmitters, said ducts being filled with liquid, means for maintaining said transmitters and said receiver normally under pressure, and locking valve means interposed in each of said individual ducts and having means for normally disconnecting the respective transmitter from the receiver and from the other transmitters, said last-named means being movable to connect the respective station to the receiver only in response to variations in pressure delivered thereto in a given direction but unresponsive to variations in pressure delivered thereto at an angle to said direction, means whereby pressure from the respective transmitter is delivered to said movable means in the given direction, and means whereby pressure from the direction of the receiver or the other transmitters is delivered to said movable means at an angle to said given direction.

2. A hydraulic remote control system comprising a plurality of transmitters, a receiver, means

for connecting said transmitters to said receiver, said last-named means including a common duct and individual ducts leading from said common duct to the respective transmitters, said ducts being filled with liquid, means for maintaining said transmitters and said receiver normally under pressure, and locking valve means interposed in each of said individual ducts and having means for normally disconnecting the respective transmitter from the receiver and from the other transmitters, said last-named means being movable to connect the respective station to the receiver only in response to variations in pressure delivered thereto in a given direction but unresponsive to variations in pressure delivered thereto normal to said direction, means whereby pressure from the respective transmitter is delivered to said movable means in the given direction, and means whereby pressure from the direction of the receiver or the other transmitters is delivered to said movable means normal to said given direction.

3. A hydraulic remote control system comprising a plurality of transmitters, a receiver, means for connecting said transmitters to said receiver, said last-named means including a common duct and individual ducts leading from said common duct to the respective transmitters, said ducts being filled with liquid, means for maintaining said transmitters and said receiver normally under pressure, and locking valve means interposed in each of said individual ducts and having means for normally disconnecting the respective transmitter from the receiver and from the other transmitters, said last-named means comprising a cylinder having a piston movable axially therein to connect the respective transmitter and the receiver, means whereby pressure from the direction of the respective transmitter is delivered to said piston axially, and means whereby pressure from the direction of the respective transmitter is delivered to said piston radially, and means for balancing said piston against the normal pressure from the direction of the respective transmitter.

from the direction of the receiver and the other transmitters is delivered to said piston radially.

4. A hydraulic remote control system comprising a plurality of transmitters, a receiver, means for connecting said transmitters to said receiver, said last-named means including a common duct and individual ducts leading from said common duct to the respective transmitters, said ducts being filled with liquid, means for maintaining said transmitters and said receiver normally under pressure, and locking valve means interposed in each of said individual ducts and having means for normally disconnecting the respective transmitter from the receiver and from the other transmitters, said last-named means comprising a cylinder having a piston movable axially therein to connect the respective transmitter and the receiver, means whereby pressure from the direction of the respective transmitter is delivered to said piston axially, means whereby pressure from the direction of the receiver and the other transmitters is delivered to said piston radially, and means for balancing said piston against the normal pressure from the direction of the respective transmitter.
